2 SHEETS—SHEET 2.

UNITED STATES PATENT OFFICE.

BÉLA TOMKAY, OF GARY, INDIANA.

MANUALLY-PROPELLED AEROPLANE.

1,412,907.

Specification of Letters Patent. Patented Apr. 18, 1922.

Application filed October 25, 1921. Serial No. 510,306.

To all whom it may concern:

Be it known that I, BÉLA TOMKAY, a citizen of Hungary, residing at Gary, in the county of Lake and State of Indiana, have 5 invented certain new and useful Improvements in Manually-Propelled Aeroplanes, of which the following is a specification.

This invention relates to manually propelled aeroplanes, and it has for an object to 10 provide a simple arrangement whereby such an aeroplane may be given an initial run along the ground and then launched into the air and propelled therethrough.

A further object of the invention is to provide 15 a novel form of propeller arranged to give a combined lifting and propelling action.

For further comprehension of the invention, and of the objects and advantages there- 20 of, reference will be had to the following description and accompanying drawings, and to the appended claims in which the various novel features of the invention are more particularly set forth.

25 Fig. 1 of the drawings is a side elevation, with the lifting plane partly in vertical section, of a manually propelled aeroplane constructed according to the invention.

Fig. 2 is an underside plan view thereof.

30 Fig. 3 is a front view.

Fig. 4 is a detail elevation of one of the propellers with its drive shaft and support, showing these parts as they appear when the machine is seen in front view.

35 Fig. 5 is a detail elevation of the same parts at right angles to Fig. 4.

In constructing my improved manually 40 propelled aeroplane I provide a frame 10 resembling an elongated bicycle frame and mounted on a pair of bicycle wheels 11. From the front and rear ends of this frame posts 12 and 13 project upwardly and have mounted on their upper ends a lifting plane 14. The front post 12 is of Y-form and the 45 lifting plane 14 is pivotally attached to its branched upper end as at 15. At the rear end a pair of transversely spaced posts 13 are provided and are connected at their lower ends by suitable cross braces to the 50 frame 10. A seat 10' is provided between the posts 13.

The rear posts 13 have also a pivotal connection with the lifting plane by means of a short link 16 and are of telescopic construction, the upper section of each post fitting into the lower section and having a

foot 17 on its lower end projecting outwardly through a vertical slot in the lower section. A coiled tension spring 18 connects this foot with a head 13' fixed to the top of the 60 lower section. From the upper post section a pair of springs 19 lead respectively upwardly and forwardly and upwardly and rearwardly to the lifting plane. The rear end of the lifting plane may be depressed, 65 to give the plane the proper angle of incidence for raising in the air, by means of a cord or wire 20 attached thereto and leading around a pulley 21 to a hand lever 23 pivoted on the frame 10 and provided with well 70 known locking means.

At the rear of the lifting plane a rudder 25 is mounted, being operated by ropes 26 connected to a tiller bar 27 and leading forwardly to a second transverse bar 27 oper- 75 able by a handwheel 28 on frame 10.

For propelling my improved aeroplane I provide a pair of rotary propellers each comprising a pair of radially projected flat blades 30 mounted to make a quarter turn on 80 their radial axes. These blades are fixed on a rod 31 suitably journaled in a box 32 fixed to the end of a transverse shaft 33, it being understood that a propeller is mounted on each end of this shaft. This shaft 33 is rotated by means of a sprocket chain 34 looped over a sprocket wheel 35 thereon and over a sprocket wheel 36 carried by the frame 10 and rotated in a well known manner by 85 pedals 37.

The blades 30 on the opposite ends of rod 31 are arranged at an angle of ninety degrees to one another and means are provided to rock the rod at the proper time so as to cause the blade which is moving forwardly 95 to cut the air edgewise, and the blade which is moving rearwardly to beat the air with its flat face. To this end a semi-circular cam disk 40 is fixed to frame 10 concentric to the propeller shaft 33 and parallel to the plane 100 of movement of the propeller. This disk 40 is adapted to be engaged at each turn of the propeller by a finger 41 fixed to rod 31 and acting in conjunction with a spring 42 to hold the forwardly moving blade edgewise 105 to the air. The spring 42 may be coiled around the rod 31 in a recess in head 32 and connected at one end to the rod and at its opposite end to the head. When the finger 41 rides off the cam 40 the spring 42 gives 110 the rod 31 a quarter turn, bringing a lug 44 on the rod into engagement with a stop 45

on the head 32 and holding the rod against rotary movement until the finger 41 again engages the cam disk.

It is believed that the manner of operation 5 of my improved manually propelled aeroplane will be readily understood from the above description, the operator sitting on the seat 10 and working the pedals 37 to revolve the propeller blades 30. When sufficient 10 speed has been obtained lever 22 is pulled to give the plane 14 an upward angle of incidence and cause the aeroplane to lift.

Having thus described my invention what I claim as new and desire to protect by Letters Patent of the United States is as follows:

1. A manually propelled aeroplane comprising a frame, front and rear wheels on which said frame is mounted, a post of Y-form projecting upward from the front of 20 said frame, a pair of transversely spaced posts of telescopic construction at the rear end of said frame, a lifting plane pivoted upon the branched upper end of said front 25 post, links connecting the upper ends of said rear posts with said plane, a spring element acting to move the rear end of said

plane upward, and means for moving the rear end of said plane downward and locking it in adjusted positions against upward 30 movement.

2. A manually propelled aeroplane comprising a frame, front and rear wheels on which said frame is mounted, a post of Y-form projecting upward from the front of 35 said frame, a pair of transversely spaced posts of telescopic construction comprising upper sections fitting into lower sections at the rear end of said frame, said lower sections being vertically slotted and said upper sections having feet projecting through said slot, tension springs connecting said feet to the upper ends of the lower sections, a lifting plane pivoted on the branched upper end of said lower post, links connecting said 40 plane, with the said upper rear post sections, and means for moving the rear end of said plane downward against such spring and locking it in adjusted positions against upward movement.

In testimony whereof I have affixed my signature.

BÉLA TOMKAY.
